DESIGN FOR A POWDER CONTAINER

John P. Wilde, Sands Point, N. Y.

Application December 13, 1945, Serial No. 124,707

Term of patent 3½ years

(Cl. D58—17)

To all whom it may concern:

Be it known that I, John P. Wilde, a citizen of the United States of America, residing in Sands Point, county of Nassau, and State of New York, have invented a new, original, and ornamental Design for a Powder Container, of which the following is a specification, reference being had to the accompanying drawing, forming a part thereof.

Fig. 1 is a top view of a powder container showing my new design;

Fig. 2 is a side elevational view.

What I claim is:

The ornamental design for a powder container, as shown.

JOHN P. WILDE.
